INVENTOR:

DAVID CROWTHER.
By Whitley and Ruckman
ATTORNEYS.

UNITED STATES PATENT OFFICE.

DAVID CROWTHER, OF MINNEAPOLIS, MINNESOTA.

DEVICE FOR HOLDING HYPODERMIC NEEDLES WHILE SHARPENING THE SAME.

1,426,965.

Specification of Letters Patent. Patented Aug. 22, 1922.

Application filed June 1, 1920. Serial No. 385,621.

To all whom it may concern:

Be it known that I, DAVID CROWTHER, a citizen of the United States, residing at Minneapolis, in the county of Hennepin and State of Minnesota, have invented certain new and useful Improvements in Devices for Holding Hypodermic Needles While Sharpening the Same, of which the following is a specification.

10 My invention relates to devices for holding hypodermic needles while sharpening the same. An object of my invention is to provide a device by means of which hypodermic needles such as used by dentists and 15 physicians may be readily sharpened with an inclined surface at the point so as to produce a point which will readily penetrate the flesh of the patient without causing the 20 sensation of pain which occurs when blunt needles are used.

The full objects and advantages of my invention will appear in connection with the detailed description thereof and the novel features embodied in my inventive idea will 25 be particularly pointed out in the claims.

In the drawings, which illustrate my invention in a preferred form and in modified forms,—

Fig. 1 is a top plan view of one form of 30 my device. Fig. 2 is a plan view showing the upper clamping member removed from the lower clamping member and turned over. Fig. 3 is an end elevational view showing the two clamping members separated as in 35 Fig. 2. Fig. 4 is a view in vertical section on the line 4—4 of Fig. 1. Fig. 5 is an elevational sectional view of a slight modification. Fig. 6 is a side elevational view of another modification. Fig. 7 is a top plan view 40 of the form shown in Fig. 6. Fig. 8 is an enlarged elevational view of a hypodermic needle after it has been sharpened.

Referring to the particular construction shown in the drawings, the numeral 10 designates an upper clamping member and the numeral 12 designates a lower clamping member. Two studs 14 and 16 are tightly secured to the lower clamping member and these studs extend through holes 18 and 20 50 in the upper clamping member with sufficient freedom to permit sliding movement of the upper clamping member on the studs. The two clamping members are held together in the following manner so that a limited 55 sliding or upward movement of the upper clamping member is permitted while the two

clamping members can be clamped together after a hypodermic needle which it is desired to sharpen has been placed between the same. A bolt 22 is provided with screw 60 threads except at its upper end 24, which is left blank or without threads. A nut 26, preferably knurled, is internally threaded so as to fit the threads of the bolt 22. This nut is provided at its upper side with a socket 65 28 to afford clearance for the unthreaded end 24 of the bolt, and the nut if desired may be provided on its other side with a reduced portion 30. The nut is screwed upon the bolt 22 from the lower end thereof, being 70 prevented from screwing off the upper end on account of the unthreaded portion. The lower end of the bolt is then inserted through a hole 32 in the upper member and through a registering hole in the lower member, and 75 this end of the bolt is then headed at 34, as best shown in Fig. 4. The two clamping members are thus prevented from becoming detached from each other, while by turning the nut 26 they may be clamped and unclamped. The inner face of at least one of the clamping members, as for instance the one designated 10, is provided with grooves 80 36, 38, 40 and 42 extending across the four corners. These grooves are inclined at different angles relatively to the sides of the clamping member for a purpose which will presently appear, and the grooves are preferably V-shaped and enlarged at the ends of the clamping member as shown at 44. The 85 form shown in Fig. 5 differs from that shown in Figs. 1 to 4 only in the provision of a coiled spring 46 which is placed in a recess in the upper face of the upper clamping member so as to surround the bolt 22 and engage the lower face of the nut 26. In this manner the two clamping members will be held together yieldingly when the nut 26 is loosened. The modification shown in Figs. 90 6 and 7 includes two clamping members 48 and 50 connected by a bow-spring portion 52 which serves to hold the clamping members together resiliently. The face of at least one of the clamping members is provided with two grooves 54 and 56 extending across the 95 corners thereof at different angles. If desired grooves may be made in the faces of both of the clamping members 48 and 50 as well as of the clamping members 10 and 12.

The operation and advantages of my invention will be obvious from the foregoing description. By referring to Fig. 8 it will 110

be observed that since a hypodermic needle such as indicated at 58 is hollow, it is best sharpened by providing the point thereof with a single inclined surface. Upon loosening the nut 26 the needle can be pushed through any one of the grooves, such as the groove 36 shown in Fig. 2. The enlarged end of the groove at 44 permits ready insertion of the needle. The point of the needle is allowed to project slightly at the other end of the groove, and upon turning down the nut the needle will be held firmly in place so that its point can be readily and accurately sharpened by rubbing the device over a whetstone or other abrasive surface. In the form shown in Figs. 6 and 7 the needle may be readily inserted in either of the grooves and will be held therein sufficiently for sharpening purposes on account of the resiliency of the spring portion 52. By referring to Fig. 8 it will be seen that the point of the needle is in this manner provided with a single inclined surface having sharp cutting edges which will readily penetrate the flesh 25 of the patient without causing the painful sensation which is produced by the use of needles having a blunt point. The length which is given to the sharpening incline may be varied according to which one of the 30 grooves is selected.

I claim:

1. A device for holding hypodermic needles while sharpening the same comprising two clamping members, and means for holding said members with their contiguous faces in contact, one of said faces being provided with a plurality of grooves inclined at different angles and any one of which is adapted to receive the needle which 35 is to be sharpened whereby the length of the sharpening incline of the needle may be varied.

2. A device for holding hypodermic needles while sharpening the same comprising two clamping members, means for guiding one of said members for relative movement toward and away from the other of said members, a screw-threaded bolt attached to one of said members and extending loosely through a hole in the other of said members, and a nut threaded on said bolt whereby said clamping members may be held with their contiguous faces in contact, one of said faces being provided with a plurality of grooves inclined at different angles and any one of which is adapted to receive the needle which is to be sharpened whereby the length of the sharpening incline of the needle may be varied.

3. A device for holding hypodermic needles while sharpening the same comprising two clamping members, guide studs secured to one of said members and extending slidably through holes in the other of said members, a screw-threaded bolt secured at one end to one of said members and passing loosely through a hole in the other of said members, the other end of said bolt being unthreaded and slightly larger than the threaded portion, and a nut threaded on said bolt between the unthreaded end of the latter and the face of the adjacent clamping member whereby said clamping members may be held with their contiguous faces in contact, one of said faces being provided with a plurality of grooves inclined at different angles and any one of which is adapted to receive the needle which is to be sharpened whereby the length of the sharpening incline of the needle may be varied.

In testimony whereof I hereunto affix my signature.

DAVID CROWTHER.
